CASE FOR CONTACT LENSES AND
SIMILAR ARTICLES

George Nissel, 6 Glentworth St., Baker St.
London NW. 1, England

Filed Aug. 15, 1966, Ser. No. 3,476

Term of patent 7 years

(Cl. D57—1)

FIG.1

FIG.2

FIG.3

FIG.4

FIG. 1 is a front elevational view of a case for contact lenses and similar articles, shown in partially open position, showing my new design;

FIG. 2 is a cross-sectional view thereof, taken on the line 2—2 of FIG. 1;

FIG. 3 is a top plan view thereof.

FIG. 4 is a top plan view of the case, shown in fully closed position, taken on a reduced scale.

It is to be understood that the broken lines shown on the drawing are intended to indicate stitching.

I claim:

The ornamental design for a case for contact lenses and similar articles, as shown and described.
